[57] **CLAIM**

The ornamental design for a portable laboratory analyzer, as shown and described.

DESCRIPTION

FIG. 1 is a front side elevation view of my portable laboratory analyzer;

FIG. 2 is a rear side elevation view thereof;

FIG. 3 is a top plan view thereof;

FIG. 4 is a left side elevation view thereof;

FIG. 5 is a right side elevation view thereof; and,

FIG. 6 is a bottom plan view thereof.

The broken line showing of the carrying case in the FIGS. 1 through 6 is for illustrative purposes only and forms no part of the claimed design.
